I. Kitsee Inventor

UNITED STATES PATENT OFFICE.

ISIDOR KITSEE, OF PHILADELPHIA, PENNSYLVANIA, ASSIGNOR OF ONE-HALF TO WILLIAM J. LATTA, OF PHILADELPHIA, PENNSYLVANIA.

TELEGRAPHY.

No. 831,288.

Specification of Letters Patent.

Patented Sept. 18, 1906.

Application filed November 22, 1905. Serial No. 288,550.

To all whom it may concern:

Be it known that I, ISIDOR KITSEE, a citizen of the United States, residing at Philadelphia, in the county of Philadelphia and 5 State of Pennsylvania, have invented certain new and useful Improvements in Telegraphy, of which the following is a specification.

My invention relates to an improvement in electric telegraphy, and has more special 10 reference to the receiving device for such telegraphy. One of its objects is to prevent sparking or sticking on receiving device. A second of its objects is to produce an efficient translating device.

15 In long-distance lines, especially in lines with large capacity—such, for instance, as submarine cable—the receiving instrument has to be of great sensitiveness, and if it is desired to use the same as a relay in conjunction with a local-circuit-containing translating device the great disadvantage arises that through the opening and closing of the local circuit sparking and therefore sticking the movable part of the relay cannot be avoided; 20 and it is, as said above, one of the aims of my invention to overcome this difficulty.

Referring to the drawing, which illustrates in partially diagrammatic and partially plan view my invention, A designates the sensitive relay connected in the line of transmission. This relay is here shown as one of the well-known types of polarized devices with stationary electromagnets, and in this device 30 a designates the movable lever, and a' and a'' 35 the two points of contact, respectively.

C designates the localized translating device, here shown as a common sounder provided with my improvements. Of this device c is the movable lever, provided with the 40 adjustable screw c', insulated from said lever by the insulating-pieces c¹⁴. This screw has, as in the usual sounder, the office to adjust the downstroke of the movable lever. c⁴ is a metallic bracket provided with the adjustable screw c''. This screw performs the office, as in the usual sounder, to adjust the upper stroke of the lever. c⁴ is a set of electromagnets—such, for instance, as usually employed in sounders—and c⁵ is the armature therefor; 45 but in addition to this set of electromagnets I provide instead of the usual spring a second set of electromagnets, (here designated as c¹² and provided with the armature c¹³.) The le-

ver c is pivoted at c¹⁵ and is provided with a device adapted to equalize the weight of both halves of the lever. This equalizing device is here shown as a movable weight c¹¹, a screw-threaded rod c¹⁰, and uprights c¹⁶. The coil of the electromagnet c⁴ is provided with the binding-posts c⁶ and c⁷, the terminals of said coil being, as usually, connected to said binding-posts. The coil of electromagnet c¹² is provided with binding-posts c⁸ and c⁹, and the terminals of this coil are connected to these binding-posts.

D is the local circuit, here shown as to comprise a source of current d and two resistances, (designated, respectively, as d' and d'') The circuit is also provided with the switch d³. One pole of the source d is connected, 70 through wire 1, with one terminal of the resistance d'. The other pole of the battery is connected with interposition of the switch d³ through wire 3 with one terminal of the resistance d''. Both of these resistances are 75 joined together through wire 2.

The electrical connection between the relay A, the translating device C, and the circuit D is as follows: The movable lever a of the device A is connected, through wire 7, with wire 2. The contact a' is connected, through wire 12, with binding-post c⁸ of the electromagnet c¹². The other binding-post c⁹ of said electromagnet is connected, through wire 6, with one terminal of the resistance d''. The contact a'' is connected, through wire 5, with the binding-post c⁷ of electromagnet c⁴, and the binding-post c⁶ of said electromagnet is connected, through wire 4, with one terminal of the resistance d''. From this description it is readily seen that through the movement of the armature a a circuit is closed around one or the other of the resistances d' and d''. It is supposed that the armature now rests, as is illustrated in the drawing, 90 against the contact a'. The circuit closed around d'' consists of the following: wire 7, armature a, contact a', wire 12, binding-post c⁸, coil of electromagnet c¹², binding-post c⁹, and wire 6. It is supposed that the coil of the electromagnet c¹² has a resistance of twenty ohms, and as the resistance of the other wires and connections do not reach the value of one ohm it may be taken for granted that the resistance of this circuit is not larger 95 than twenty-one ohms. It is now supposed

that the value of the resistance d' is about one hundred ohms, and as the current flows in inverse proportion it is obvious that as long as the armature a will rest against the 5 contact a' the current from the source d will flow in its greater part through coil of electromagnet c^{12} , will energize this electromagnet, and will therefore draw its armature c^{13} downward, whereby the lever c will assume 10 the position as illustrated in the drawing—that is, the lever end near this electromagnet will be down and the opposite end up. When now the armature a of the relay A moves from a' toward a^2 , the lever c will still remain 15 in this position, for the reason that no force is present to alter this position; but as soon as the armature a connects with the contact a^2 a circuit will be established around the resistance d^2 , consisting of wire 7, armature a , contact a^2 , wire 5, binding-post c^7 , coil of electromagnet c^4 , binding-post c^6 , and wire 4, and as the resistance value of this 20 circuit is lower than the value of the resistance d^2 —twenty-one against one hundred—the current will flow through the circuit including electromagnet c^4 , energizing the same and drawing its armature c^5 , and therefore the right-hand side of the lever c , downward till the screw c' touches the bracket c^2 . 25

30 To obviate the sticking and sparking in the relay A, I have recourse to the following arrangement: The bracket c^2 is connected, through wire 8, with wire 2, being the junction of the resistances d' and d^2 . The lever 35 c is, through wire 10, binding-post c^9 , and wire 6, in electrical connection with one terminal of resistance d' , and the insulated screw c' is, through wire 9, in electrical connection with one terminal of resistance d^2 .

40 The working of the whole arrangement is as follows: Normally—that is, when not in use—the armature a of the relay A is made to rest on contact a' through the action of the established circuit including coil of electromagnet c^{12} . The end of the lever c near the magnet c^{12} will be pulled downward and the opposite end therefore be pulled upward till the lever end strikes the screw c^3 ; but as the lever c is in electrical connection with one 45 terminal of resistance d' and the bracket c^2 , and therefore screw c^3 , in electrical connection with the other terminal of said resistance d' , and as this circuit is of very low resistance as compared with the resistance d' or the resistance 50 of the circuit including electromagnet c^{12} the current will cease to flow through said electromagnet, and therefore through the junction between armature a and contact a' , as soon as the lever end touches the screw c^3 ; 55 but the ceasing of this flow of current will, as said above, not alter the position of the lever c , and the same will remain in this position till the circuit including the electromagnet c^4 is established. Should now the operator 60 send an impulse over the line which ener-

gizes the relay A in a manner so as to move the armature a away from contact a' and toward, to, and in connection with contact a^2 , the circuit including a' will be broken; but as through the former establishing of the low- 70 resistance circuit comprising wires 6 and 10, lever c , screw c^3 , bracket c^2 , and wire 8 the flow of the current was before this breaking occurred diverted from the circuit embracing a' it is obvious that no sparking will follow 75 the breaking away of the armature a from a' , and therefore the sticking of the armature, a result of the heating effect of the current, will entirely be obviated; but the lever c will still remain in its normal position till the armature comes to a rest against a^2 , establishing the circuit including electromagnet c^4 . The flow of the current in this circuit will, as 80 said above, move the lever in opposite direction—that is, will bring the end near bracket c^2 85 downward—till the screw c' comes in contact with the extended part of the bracket c^2 ; but as this screw is connected with one terminal of the resistance d^2 —the bracket with the other terminal of said resistance—a short circuit of far lower resistance than d^2 or the circuit including a^2 is established, and the current will be diverted from the circuit including a^2 and will flow practically in its entirety 90 through the short circuit. Should now the 95 operator send an impulse over the line resulting in the breaking away of armature a from a^2 , the circuit including a^2 will be broken; but as no current is flowing in this circuit at the 100 moment of separating armature a from contact a^2 no sparking or sticking will result from this separation.

Persons versed in the art will readily understand that the arrangement, as above described and illustrated in the drawing, is designed to be used in connection with a system of telegraphy, whereby an impulse of one polarity is used to produce a symbol of the alphabet, and whereby an impulse of opposite polarity is used to complete a symbol, 105 and whereby the length of time elapsing between two impulses characterizes the nature of such symbols—that is, if the same symbolizes a dot or a dash. It is now supposed that the transmitted impulse, sending the 110 armature a toward, to, and in contact with a^2 , is the signaling impulse, and the impulse sending the armature toward, to, and in contact with a' is the terminating impulse. The method of sending and receiving messages is 115 then a very simple one. The operator if desirous to transmit a dot sends, say, a positive impulse over the line, closing the circuit embracing a and a^2 and sends after one unit of time the negative impulse over the wire, 120 which will break the circuit including a^2 , but will make the circuit including a' . The first impulse will bring the lever end near the bracket down and the screw c' in contact with said bracket. It will therefore produce 125 130

on the sounder a movement which is called the "downstroke." The second impulse will produce on the sounder an upward movement of the lever, till its end strikes against the screw c^3 , and this movement is known by persons versed in the art as the "upper" stroke. If the operator desires to transmit a dash, he will first send the positive impulse and will then wait two or three units of time till he sends the opposing or negative impulse, and the receiving operator will readily recognize by the time unit a lapsing between the first and second impulse the value of the character received—that is, if the same is meant to be a dot or a dash.

I am aware that instead of the circuit arrangement as illustrated each of the contacts a' and a^2 may be provided with a separate circuit; but I prefer the arrangement as illustrated, as the same has proven in practice more satisfactory.

Having now described my invention, what I claim as new, and desire to secure by Letters Patent, is—

1. In telegraphy a line of transmission, a polarized relay in said line, a local circuit connected to said relay, translating device in said circuit and means dependent on the movement of the movable part of said translating device to establish a shunt around the circuit connected to said relay and including said translating device.

2. A telegraphic system embracing at the receiving station a polarized relay, a localized circuit for said relay, an electromagnetic device for said circuit, two sets of electromagnets for said device and means, therefore, to establish a short circuit around said localized circuit; the relay, the electromagnetic device, the localized and short circuit all in operative relation as to each other.

3. In combination with a telegraphic relay connected in the line of transmission, a translating device connected to a localized circuit, movable means operated by said relay to open and close said circuit and means for said translating device to divert the flow of the current from the parts of the relay connected to said circuit, before said circuit is broken through the movement of the movable means of said relay.

4. In telegraphy means to prevent the sparking and sticking in a relay—due to the breaking of a localized circuit through the movement of the armature of said relay, said means embracing electromagnetic means

adapted to create a shunt around the circuit connected to said relay.

5. In combination with a relay connected to the line of transmission, a sounder provided with two sets of electromagnets, a circuit for each set, means for said relay to close an electric circuit including one of said sets, through the movement of its armature in one direction and to close an electric circuit including the second set, through a movement of the armature in the opposite direction, and means operatively related to said sounder to divert the flow of the current from that part of the circuit which is connected to the relay proper.

6. In telegraphy a relay connected to the line of transmission, a movable armature for said relay, a localized electric circuit operatively connected to said relay, a translating device in said circuit, the terminals of said circuit adapted to be closed or opened through the movement of the armature of said relay and means operatively connected to the translating device to divert the flow of the current from said relay after the terminals have been closed through the armature of said relay.

7. In combination with a relay connected to a line of transmission a local circuit normally closed, two resistances of a comparatively high value for said circuit, a branch circuit for each of said resistances, a translating device provided with two sets of electromagnets, one set included in one branch circuit and the second set included in the second branch circuit, said branch circuits adapted to be opened and closed through the movement of the armature of said relay and means at said translating device to divert the flow of the current from one or the other of the branch circuits.

8. In telegraphy means to prevent sparking or sticking in a polarized relay connected to a localized circuit embracing an electromagnetic device, said means embracing means operatively connected to said electromagnetic device and adapted to establish a shunt around the localized circuit, thereby diverting the flow of the current from said localized circuit into said shunt-circuit.

In testimony whereof I affix my signature in presence of two witnesses.
